HARRY WILLIAMS, OF GLASGOW, SCOTLAND.

DRIVING MECHANISM.

1,162,119.

Specification of Letters Patent. Patented Nov. 30, 1915.

Application filed April 30, 1912. Serial No. 694,189.

To all whom it may concern:

Be it known that I, HARRY WILLIAMS, subject of the King of Great Britain, residing at Glasgow, Scotland, have invented 5 certain new and useful Improvements in Driving Mechanism, of which the following is a specification.

This invention relates to improved driving gear for use in steam, gas, oil and like 10 engines or for pumps and like driven appliances.

The object of the present invention is to render the power applied more effective at an earlier stage in and throughout the reciprocation of the sliding member, that is to say to render the effort more effective and more uniform at the beginning of and throughout the stroke.

To this end I cause the crosshead end of 20 a connecting rod to follow a curved path which is arranged about or adjacent to the path of the sliding member and is composed of the combination of a considerable oscillating movement about a pin on the sliding member, conveniently about 180° , and the reciprocating movement of the sliding member. For this purpose I propose to employ revolving crank pins at a fixed angular relation, two connecting rods and an oscillating 25 lever or its equivalent on the slider. The essential of the present invention, is that the connecting rods at an early stage in and during the motion tend to successively come into a tangential position with 30 respect to the crank and for this purpose the oscillating lever must have its arms of a radius less than the crank and preferably about one-half the crank radius, which is a novel relation productive of the effect stated.

40 The cranks moreover should not be more than about 90° apart. In other words, the distance between the outside centers of the oscillating link should be equal to or only very slightly greater than the chord joining 45 the centers of the two crank pins. With this construction, the oscillating lever swings through an angle of about 180° , and the centers of the levers follow a path like a horizontal 8, with the two loops of the 50 very nearly touching the straight line path

of the center of the oscillating lever. It should also be stated that the radius of revolution of the crank pins is greater than half the piston or slider stroke.

In practice, I have found after a series of 55 rigorous tests that a considerable increase in the brake horse power with the same steam consumption may be obtained by substituting my novel driving gear for the ordinary gear. A pumping test has shown that the 60 fluid friction losses with this improved gear are materially reduced owing to the peculiar relation of the piston speed to the port or valve opening throughout the stroke. The engine runs more steadily and the maximum 65 stress on the working parts is also reduced by a material amount owing to the greater uniformity of the effort.

The invention may further be said concisely to consist in a driving gear for an 70 engine pump or the like comprising two cranks, of a radius greater than half the piston stroke, connected by two connecting rods to the opposite ends of a lever pivoted at its center on the crosshead or sliding member 75 and having its arms of a lesser radius than the crank, whereby the oscillating lever swings through an angle of about 180° during each revolution of the crank. The cranks should not be more and are preferably 80 less than about 90° apart and the centers of the pins on the oscillating link are approximately the same distance apart as the chord joining the crank pin centers. The connecting rods are preferably arranged 85 to cross at the inner dead center of the cranks, that is when the crank pins are nearest to the path of reciprocation of the slider or reciprocating member.

Referring now to the accompanying 90 drawings which illustrate this invention in one form, Figure 1, is a side elevation of one form of the mechanism which I may employ. Fig. 2, is a plan. Fig. 3, is an end elevation looking on the cranks and Fig. 4, 95 is a diagrammatic representation of the essential parts of the gear shown in Fig. 1. Fig. 5, is a side view and Fig. 6, is a plan of a modified construction.

In carrying out the invention according 100

to the particular form illustrated in the drawings as applied to an engine. The cross-head sliders *a*, have freely mounted within them pins *b*, on which two oscillating disks 5 *c*, *d*, are fixed. The pins *b*, are also embraced by the forked end *e*, of the piston rod *f*, which is continued rearwardly and connects to the piston *f'*, in an ordinary manner. The piston *f'*, reciprocates in the 10 cylinder *f''*. The pins *b*, are continued laterally through the disks *c*, and *d*, and are suitably riveted or otherwise fixed therein. The disks *c* and *d*, are further connected by pins *g* and *h*, arranged diametrically opposite one another. 15

It is evident that the two disks may each be narrowed so that they become mere links or levers, just as a common crank plate may be changed to a simple crank, and in Fig. 4 20 I have shown, diagrammatically, what is in effect a centrally pivoted lever *G*, *H*, the two disks being essentially two rigidly connected, oppositely extending cranks.

The pins *g* and *h*, are connected by connecting rods *i* and *j*, respectively to crank pins *k* and *l*. The crank pin *l*, is fixed on a crank disk *m*, and the crank pin *k*, is fixed on a crank disk *n*. The two crank pins *k* and *l*, are connected by a link *o*. The connecting rods *i* and *j*, are conveniently offset as shown. The rods *i* and *j*, may be arranged to cross at the outer dead center, but it is preferable to arrange them open at the outer dead center as shown in Fig. 1, as by 30 this arrangement the advantages of this invention are obtained in a greater degree. The centers of the pins *g* and *h*, are also preferably slightly farther apart than the centers of the pins *k* and *l*, but the centers 35 of the pins *g* and *h*, should always be nearer together than twice the crank radius. 40

The advantages of this invention are however, obtained in a very much decreasing degree if the cranks exceed 90° apart and if 45 the centers on the oscillating link are farther apart than $R\sqrt{2}$, where *R* is the crank radius. The best results are obtained with an angle rather less than 90°, for the cranks and the centers of the oscillating link correspondingly reduced. 50

It will be seen from the above that owing to the opening and crossing of the connecting rods *i* and *j*, I am able to shorten the piston travel considerably, while maintaining the 55 same crank path. The amount of the variation in the length of the intermediate gear or linkage between the piston *f'*, and the crank pin is exemplified by the relative lengths *L* and *L'* in Fig. 1, which shows the 60 lengths at the two end positions of the piston. This results in a still greater increase in leverage with a shorter piston stroke than would be obtained by using open rods at the inner dead center. It will be seen that by

means of this invention I reduce the volume 65 of displacement in the cylinder at each end of the stroke and the total amount of this reduction is equal to the difference between the diameter of the crank pin circle and the piston travel. 70

The advantages of increasing the diameter 75 of the crank pin circle, for any given piston travel, will be readily appreciated by those engaged in this art, as it results among other things in giving a more uniform turning moment and reduces the losses incurred in transforming reciprocatory into rotary motion and vice versa. 75

With the driving gear illustrated the pins 80 *g* and *h* each travel in a double looped path resembling a horizontal 8, with its two loops lying approximately but not quite on the plane of motion of the crosshead as shown at *Z* by dotted lines in Fig. 4. The cross-head ends *G* and *H*, of the connecting rods 85 are thus caused to recede or double back at opposite ends of the piston stroke. Thus on reference to Fig. 4, it will be seen that the pin *G*, recedes when the link travels from right to left. At the opposite end of the stroke, the pin *G*, will recede or double back when the piston starts its motion from left to right. If the rotation were reversed the pin *H*, would recede and double back. It should also be pointed out that by virtue of 90 the curved path of the pins *g* and *h*, the rods *i* and *j*, successively tend to assume the nearest possible position to the tangential and thereby the piston pressure is transmitted in 95 the case of engines in the most favorable 100 fashion to the crank shaft. About the center of the piston stroke, the two rods are both approximately parallel. 100

On plotting out the piston velocities with a uniform angular velocity of the crank, 105 it is found that the initial piston velocity is considerably less with this form of driving gear, than with the ordinary form of connecting rod. This reduction in the initial piston velocity gives more time for the steam 110 to enter the cylinder in steam engines and is also of material use in reducing valve losses in pumps. 110

It will be understood that it is not essential 115 for each link *C*, in Fig. 4, to be exactly centrally pivoted and means may be provided for altering the distances apart of the crank pins *K* and *L*, as for instance by altering the length of the joining link *O*, or in any other convenient manner. 120

According to another construction of this invention I dispense with the separate disks and employ a single disk which is suitably mounted in the reciprocating member. According to one form as illustrated in Figs. 125 5 and 6, this disk 6, is reduced at its central part 7, where it finds a bearing in the cross head 8. Suitable slippers 9, are fixed in any

convenient manner to the crosshead 8. The pins 16, 17, on the oscillating disk 6, are arranged on opposite sides and the connecting rods 10 are connected, so as to cross at the 5 inner dead center, to two crank pins 11 and 12. In this form also one of the crank webs is dispensed with and what is known as an overhung crank construction is employed. In this construction, I prefer to make the 10 crank 13, pins 11 and 12, and web 14, all in one piece of metal. The driving force from the pin 12, is transmitted through the web 14, pin 11 and crank 13, to the rotating shaft 15. The reduced part 7, of the disk 6, is left 15 of sufficient diameter to provide ample bearing surface for the crosshead pin. The oscillating pins 16 and 17, need not be so large. The crank pin 11, should be larger and stronger than the pin 12.

20 It will be readily appreciated by those engaged in this art that the balancing of an engine such as herein described may be carried out very fully and perfectly owing in the first place to the tangential manner in 25 which the force is transmitted to the crank pins and owing to the fact that the crossheads so far as they may not be balanced by weighting the crank may be perfectly balanced by suitably weighting the oscillating disk. In this connection it may be stated 30 however that the two connecting rods appear to balance one another to a marked degree. From comparative tests made on a small engine with a very late cut off and first with 35 my improved slider crank gear and then with an ordinary connecting rod, it would appear that approximately the same power is obtained from the two engines working with the same crank pin circle and under 40 similar conditions. This would mean that with the improved gear the same power is obtained with a much smaller stroke of piston and consequently with much less steam.

The following is submitted as another 45 probable method of regarding the improved crank gear. The displacement of the piston (in the case of an engine) before the connecting rods of my improved gear start to transmit a substantially tangential force, is 50 less than in the case of the ordinary slider crank gear and the difference in displacement between the pistons in the two gears probably gives some approximation to the reduction in steam consumption.

55 I claim:—

1. A driving gear comprising a sliding member movable in a straight line path, a rotating member having two cranks in fixed angular relation, an oscillating member on 60 the sliding member, and connecting rods connecting the cranks with diametrically opposite points on the oscillating member, the distance between said points and the axis of the oscillating member being substan-

tially less than the radius of the cranks, 65 whereby the oscillating member swings through an arc of approximately 180°, its line of centers being brought alternately approximately in parallelism with the line of movement of the sliding member. 70

2. A driving gear comprising a slider, a crank shaft having cranks set at less than 90°, an oscillating member on the slider having diametrically opposed pins, and connecting rods connecting the cranks with said pins, the distance of said pins from the axis 75 of the oscillating member being substantially less than the radius of the cranks, whereby said pins are caused to follow a closed curved path having its maximum and 80 minimum distances from the line of movement of the slider differing from each other by more than the minimum distance of said path from said line.

3. In reciprocating engines, and pumps a 85 reciprocating member, a rotating member and transmission and converting mechanism between said members comprising two crank pins maintained at an angle apart less than 90°, and moving in a circle of greater diameter than the stroke of the reciprocating member, an oscillating member mounted centrally to move with but oscillate on said reciprocating member, pins carried by said oscillating member at diametrically opposite 90 parts with respect to the center of oscillation, said pins being at distances from the center of oscillation approximately half the radial distance of the crank pins from 95 their center of oscillation, and connecting 100 rods from said pins on the oscillating member to the said crank pins.

4. In reciprocating engines, and pumps a reciprocating member, a rotating member and transmission and converting mechanism 105 between said members, comprising two crank pins maintained at an angle apart less than 90° and moving in a circle of greater diameter than the stroke of the reciprocating member, an oscillating member mounted 110 centrally to move with but oscillate on said reciprocating member, pins carried by said oscillating member at diametrically opposite parts with respect to the center of oscillation, said pins being at distances from the 115 center of oscillation approximately half the radial distance of the crank pins from their center of oscillation, and connecting rods from said pins on the oscillating member to the said crank pins, said connecting rods being arranged to cross at the inner dead center position of said cranks when said crank pins are nearest to the path of reciprocation of 120 said reciprocating member.

5. In engines and pumps, a rotating member, a reciprocating member, two oscillating plates mounted to move with but oscillate on said member, cross connecting pins be-

tween said plates said pins being set diametrically opposite to oscillate back and forward with said plates through an angle of substantially 180° , two cranks maintained at a constant angle less than 90° apart, pins on said cranks, the distance of the pins carried by the oscillating plates from the axis of the oscillating plates being substantially less than the radius of the cranks, and two

connecting rods from said crank pins to said pins on the oscillating plates. 10

In testimony whereof I have signed my name to this specification in the presence of two subscribing witnesses.

HARRY WILLIAMS.
